UNITED STATES PATENT OFFICE.

GRiffin S. ACKLEY, OF BROOKLYN, NEW YORK, ASSIGNOR TO G. S. ACKLEY & CO., OF NEW YORK, N. Y., A COPARTNERSHIP CONSISTING OF GRIFFIN S. ACKLEY AND HELEN P. ACKLEY.

BRAKE MECHANISM.

1,270,762.

Specification of Letters Patent.

Patented J 2, 1918.

Application filed April 16, 1917. Serial No. 162,290.

To all whom it may concern:

Be it known that GRIFFIN S. ACKLEY, a citizen of the United States, and resident of the city of New York, borough of Brooklyn, county of Kings, and State of New York, has invented certain new and useful Improvements in Brake Mechanism, of which the following is a specification.

This invention relates to mechanism for controlling the brakes and in its main features is adapted more particularly for use in connection with car brakes of the type in which the brake is operated by means of a chain or the like wound upon a suitable member which is generally operated manually.

The present invention is an improvement over those set forth in my prior Patents Nos. 1,002,551 and 1,158,764 and operates broadly on the same principles, comprising in its general combination a winding or power drum on which the brake chain is adapted to be wound and on which also a check chain is wound in opposition to the brake chain.

The present invention has the same general object of economy of space and easy operation as those set forth in my above mentioned previous patents while in addition it has for its objects to cheapen the construction and decrease the weight of the brake mechanism, a further object being to insure a quicker withdrawal of the brake shoe or brake proper from the wheel.

The construction by which these objects are attained will be fully set forth in the following specification taken in connection with the accompanying drawings, the various combinations and arrangements of parts constituting the present invention being more particularly set forth in the appended claims.

Figure 1 of the drawings is a face view partly broken away of a brake operating mechanism constructed according to my invention.

Fig. 2 is a vertical section at right angles to Fig. 1.

Fig. 3 is a plan view of the casing supporting the hand wheel and parts directly connected thereto.

Fig. 4 is an enlarged detail section showing the mounting of the hand wheel and its connection to the top sprocket wheel.

Fig. 5 is a detail horizontal section ap-

proximately on the line 5—5 of Fig. 1 and showing particularly the mounting of the foot operated pawl.

Fig. 6 is a front view showing a modified means of operatively connecting the hand wheel shaft to the winding drum.

Fig. 7 is a side elevation, partly broken away showing a modified manner of applying the invention to a car.

A portion of the platform of a car is shown at 1. Upon this platform, referring now more particularly to Figs. 1 and 2, is mounted an open bottomed casing or housing 2 which may be secured to the platform by any suitable means as the bolts 3. Journaled in this casing as at 5 is a horizontally disposed drum 6 to which both the brake chain 7 and check chain 8 are attached as will be pointed out in detail later.

Rigidly secured upon this drum midway between the ends thereof is a relatively large sprocket wheel 10 over which is looped a sprocket chain 11 which extends upwardly and passes over a relatively small sprocket wheel 12 fixed on a shaft 13 journaled in a second casing 14 as will be presently pointed out and adapted to be rotated by a hand-wheel 15.

The casing 14 is supported at the proper distance above the platform for convenient operation of the hand-wheel by means of a pair of pipes 20 and 21 which are screwed at their lower ends into suitable tapped openings in the top of the lower casing or housing 2 and which have the casing 14 mounted on their upper ends. As here shown the upper ends of the pipes 20 and 21 are exteriorly threaded as at 22 and pass freely through openings 23 in the bottom of the casing, the latter resting upon nuts 24 threaded on the pipes while lock nuts 25 are threaded over the ends of the pipes projecting through the openings 23 and serve to rigidly secure the casing in position. It will be apparent that by adjusting the nuts 24 and 25 on the pipes a corresponding vertical adjustment of the casing, and consequently of the sprocket wheel 12, to properly tension the sprocket chain 11 may be effected.

As will be noted the pipes 20 and 21 extend tangentially to the sprocket wheels 10 and 12 and thus serve as conduits for the opposite reaches of the sprocket chain 11.

The casing may be provided with a removable cap 14' for access to the interior there-

of. The manner of operatively connecting the handwheel to the shaft may be substantially similar to that disclosed in my previous Patent No. 1,158,764 above referred to. 5 In the present device the shaft is squared throughout a portion of its length, having at opposite ends rounded portions one of which bears in a suitable opening in one wall of the casing. Over the opposite end of the 10 shaft a sleeve 30 is placed, this sleeve bearing in a bushing 31 secured in an opening in the adjacent wall of the casing. Secured upon the sleeve 30, adjacent the inner end of the bushing, by a set screw 32 is a collar 15 33 while the handwheel 15 is fixed upon the outer end of the sleeve which is thus held against longitudinal movement. Formed on the inner end of this sleeve and the adjacent end of a second sleeve 34, which latter 20 is slidable on the squared portion of the shaft 13, are ratchet teeth 35, the sleeve 34 being normally pressed into engagement with the sleeve 30 by a coiled spring 36 bearing between the sprocket wheel 12 and the sleeve 34. This arrangement provides for the 25 backward rotation of the handwheel independently of the shaft 13. To lubricate the sprocket chain and wheels an oil cup 37 may be mounted as shown on one of the pipes 20, 30 21 the inclined position of the pipe causing the latter to form a trough to conduct the oil down upon the lower sprocket wheel.

Referring now more particularly to the mechanism contained in the housing 2, the 35 drum 6, as shown most clearly in Fig. 2, is formed in two sections, 41 and 42, between which the sprocket wheel 10 is located, the brake chain 7 winding on the section 41 and the check chain 8 on the section 42. Each 40 of these sections is spirally grooved in its periphery to receive its chain and constitutes in effect a cone increasing in diameter toward the center of the drum where each is provided with registering lugs 43 and 44 45 through which a bolt 45 is passed by means of which the chains 7 and 8 are fastened to the drum. In the construction shown in Figs. 1 and 2 the check chain 8, instead of being fastened at its opposite end to the 50 brake chain as in my previous patents is preferably carried upwardly from the drum, through a short pipe 47 screwed into the top of the housing 2, and attached at its other end to said pipe 47, being preferably 55 attached to a coiled spring 48 which may be hung from a hook 49 secured in a cap 50 on the top of the pipe 47.

The brake chain 7 passes down from the 60 drum through a suitable opening 55 in the platform 1 and over a pulley 56 located beneath the platform. As a feature of the present invention I prefer to mount this pulley in a manner to cause it to assist in the rapid unwinding of the chain when freeing the 65 brake shoes from the car wheel and to this

end the pulley is journaled in the free ends of a pair of swinging arms 57 which are pivoted as at 58 to a bracket 59 fixed to the underside of the platform. A pair of springs 60, secured at one end to the arms 57 and at opposite ends to the bracket 59 normally tend to swing the pulley in a direction away from the brake shoe. As will be apparent from the relative positions of the parts shown in Fig. 2, when the drum is freed to 70 release the brake the pulley 56 moves rapidly under the influence of the springs 60 in a manner to lengthen the path of the brake chain 7 from the drum to the brake and thus acts to cause a quick unwinding 75 of the drum and release of the brake chain. Swinging movement of the pulley in opposite directions is preferably limited by means of stops 61 and 62 formed on the bracket 59 and adapted to be engaged by the arms 57 80 as the pulley swings in opposite directions.

The drum is releasably locked against unwinding movement by means of a ratchet wheel 65 fixed thereto and engaged by a gravity-release pawl 66 which is moved 90 against the ratchet wheel by a foot lever 67 pivoted as at 68 to the housing 2 and having a slot and pin connection 69 with the pawl 66, the lever 67 projecting at its free end through an opening 70 in the housing and 95 being provided with a foot pedal 71.

It will be apparent that with arrangements of parts just described, with the power drum located as close as possible to the platform, a simple construction, and 100 one combining great strength and rigidity with a comparatively small weight, will be provided.

In Fig. 6 of the drawings I have shown a modified means for transmitting power from 105 the shaft 13 to the drum 6 in which a small drum 80 is mounted on the shaft 13 instead of the sprocket wheel 12 while the drum 6 is provided with an intermediate cylindrical section 81 in place of the sprocket wheel 110 10, a suitable rope 82 passing over these drums, being preferably attached to each drum in any suitable manner and given enough turns around each drum to permit of the necessary winding and unwinding 115 movement.

In Fig. 7 I have shown a modified application of the invention to a car and which is adapted for use in connection with a vertical brake staff.

In this modification the car platform is indicated at 85. Secured to the underside of the platform at the proper point for locating the brake staff is a casing 86 through which the lower end of the brake staff 88 125 projects. The brake staff may be provided with suitable anti-friction bearings 89 where it passes through the platform. Fixed to the brake staff just above the platform is a ratchet wheel 90 adapted to be 130

engaged by a pawl 91 to hold the brakes set. Upon the lower end of the brake staff within the casing 86 is fixed a sprocket wheel 92.

5 Secured to the underside of the car platform to the rear of the casing 86 at any point which may be desirable or convenient is a housing 95 in which is suitably journaled a drum consisting of two sections 96 and 97, corresponding to the sections 41 and 42, between which is a sprocket wheel 98, a sprocket chain 99 being looped over the sprocket wheels 92 and 98.

15 A brake chain 100 is attached to, and adapted to wind upon, the drum section 96 as in the previously described modification, while a check chain 101 is attached to the drum section 97 by a common bolt as previously described, the check chain in this 20 modification however, leading from the drum in the same direction as the brake chain 100 and being connected to the latter at a suitable distance from the drum as in my above mentioned Patent No. 1,158,764.

25 The reaches of the sprocket chain 99 are inclosed in pipes 103 and 104 corresponding to the pipes 20 and 21 and these pipes may be either set freely in suitable openings in the casing 86 and housing 95 or may be hung 30 from the car platform by suitable hangers indicated at 105 and 106.

The operation of both modifications will, it is thought, be apparent from the above mentioned description since it will be obvious that the rotation of the shaft 13 or 35 brake staff 88 will cause a corresponding rotation at reduced speed of the drums 6 and 6'. During winding of the brake chains the check chains unwind and when the brake 40 chains unwind the check chains wind and so limit the unwinding movement to obviate taking up unnecessary slack at the beginning of the winding operation.

45 As many changes could be made in the above construction and many apparently widely different embodiments of my invention designed without departing from the scope of the appended claims, I intend that all matter contained in the above description 50 or shown in the accompanying drawing shall be interpreted as illustrative merely of an operative embodiment of my invention and not in a limiting sense.

What I claim is:—

55 1. In a brake mechanism, a winding drum, a housing therefor, a pair of pipes projecting upwardly from said housing, a casing mounted on the upper ends of said pipes, a handwheel shaft mounted in said casing, and means for rotating said drum from said handwheel shaft, including a flexible member extending through said pipes.

60 2. In a brake mechanism, a winding drum, a housing therefor, a pair of pipes

projecting upwardly from said housing, a casing mounted on the upper ends of said pipes, a handwheel shaft mounted in said casing and means for rotating said drum from said handwheel shaft, including a flexible member extending through said pipes, and means for adjusting said casing vertically upon the upper end of said pipes. 70

3. In a brake mechanism, a winding drum comprising two sections each increasing in diameter from the end toward the center of the drum, a brake chain attached to one of said sections and a check chain attached to the other section. 75

4. In a brake mechanism, a winding drum comprising two sections each increasing in diameter from the end toward the center of the drum, a brake chain attached to one of said sections and a check chain attached to the other section, means for rotating said drum, said means being connected to the said drum between the said sections. 80

5. In a brake mechanism, a winding drum having two sections each of increasing diameter and upon which the brake and check chains are adapted to be wound, respectively, a housing in which said drum is mounted, a brake chain attached at one end to said drum, and a longitudinally resilient check chain attached at one end to the said drum. 90

6. In a brake mechanism, a winding drum having two sections each of increasing diameter and upon which the brake and check chains are adapted to be wound, respectively, a housing in which said drum is mounted, a brake chain attached at one end to said drum, and a longitudinally resilient check chain attached at one end to the drum 100 and at its opposite end to the housing, said check chain extending from the drum in an opposite direction to the brake chain. 105

7. In a brake mechanism, a winding drum, a housing adapted to rest on a car platform in which said drum is mounted, a pipe extending upwardly from said housing, a brake chain attached at one end to said drum and extending downwardly therefrom, and a check chain attached at one end to said drum and extending upwardly in and attached at its opposite end to said pipe. 110

8. In a brake mechanism, in combination with a brake chain and a winding drum therefor, of a bodily movable pulley over which said brake chain passes, and means acting to automatically move said pulley in a direction to unwind the brake chain from the drum when the brake chain is released. 120

9. In a brake mechanism, in combination with a brake chain and a winding drum therefor, of a pulley over which said brake chain passes, a swinging arm on which said pulley is mounted, and a spring normally 130

pulling said arm in a direction to unwind the brake chain from the drum.

10. In a brake mechanism, a winding drum, a housing in which said drum is mounted, a casing located at a distance from said housing, means for imparting rotation to said drum carried by said casing, a flexible member extending between

said last mentioned means and said drum, and a pair of pipes extending between said housing and casing and having the opposite reaches of said flexible member extending therethrough.

Signed at the city, county and State of New York, this 5th day of April, 1916.

GRIFFIN S. ACKLEY.
